UNITED STATES PATENT OFFICE.

WILLIAM C. BAXTER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-LEVELING MACHINE.

1,351,735.

Specification of Letters Patent.

Patented Sept. 7, 1920.

Application filed February 13, 1915. Serial No. 7,985.

To all whom it may concern:

Be it known that I, WILLIAM C. BAXTER, a citizen of the United States, residing at Beverly, in the county of Essex and State of Massachusetts, have invented certain new and useful Improvements in Sole-Leveling Machines; and I do hereby declare the following to be a full, clear, and exact description of the invention, such as will enable others skilled in the art to which it appertains to make and use the same.

The invention relates to sole leveling machines of that type in which the leveling of the sole is effected by a vibrating leveling roll which is caused to travel along the sole and to change its relative lateral inclination by relative movement of the roll carrier and jack on which the shoe is supported.

In operating upon certain classes of work the leveling of the sole may be facilitated, and a better finish given to the sole, if the sole is subjected to heat as well as pressure during the leveling, and it is the object of the present invention to provide novel and improved means by which this result may be secured in a reliable and satisfactory manner in leveling machines of the type referred to. To this end the invention contemplates the provision of means for heating the leveling roll or rolls during the leveling operation. In the preferred form of the invention the leveling roll is mounted on a hollow shaft secured in the vibrating roll carrier, and provided with radial holes forming gas jets to which gas is supplied through suitable piping connected with the end of the shaft. With this construction the roll may be readily and economically heated to the desired temperature without interfering with the proper operation of the roll upon the sole.

The invention will be readily understood from an inspection of the accompanying drawings and the following detailed description of the mechanism illustrated therein.

In the drawings, Figure 1 is a side elevation showing an automatic leveling machine embodying the invention in its preferred form; Fig. 2 is a detail side elevation showing the roll carrier and the devices for heating the roll; and Fig. 3 is a sectional plan view of the parts shown in Fig. 2.

In the drawings the invention is illus-

trated as embodied in an automatic leveling machine having substantially the construction and mode of operation of the machine shown and described in Patent No. 1,011,301, December 12, 1911, and Patent No. 555,548, March 3, 1896. This machine comprises generally two shoe supporting jacks, two vibrating leveling rolls coöperating respectively therewith, mechanism for actuating the jacks to change the relative longitudinal position of the jacks and rolls, means for connecting and disconnecting each jack and the jack oscillating mechanism, and means for tipping the rolls to change the relative lateral inclination of a jack and its coöperating roll during the leveling operation.

In Fig. 1 the jacks 2 are shown in the position which they assume when disconnected from the jack oscillating mechanism. The jacks are pivotally mounted at 4 in the front of the machine frame, and are adapted to be connected with the jack oscillating mechanism, which is the same in construction and mode of operation as the jack oscillating mechanism of the patents above referred to. The leveling rolls 6 are mounted to vibrate in roll carriers 8 secured to sleeves 10 mounted to turn in roll carrying beds 12 which are pivotally mounted at 14 in the upper rear portion of the machine frame. The sleeves 10 are rocked during the leveling operation to change the lateral inclinations of the rolls by mechanism which is fully described in the patents above referred to. Each roll 6 is mounted to turn freely upon a shaft 16, the ends of which are mounted in the arms 18 of a yoke, the rear end of which is connected to the front end of a rod 20. The rod 20 passes through the center of the roll carrying sleeve 10 and is rapidly reciprocated to vibrate the leveling roll by an eccentric secured to the constantly rotating shaft 22. The forward ends of the yoke arms 18 are guided in ways 24 formed in the side bars of the roll carrier 8, and serve to support and guide the yoke and leveling roll as the yoke and roll are vibrated.

In embodying the invention in a leveling machine having the construction above described, the shaft 16 is provided with a central bore 26 and with radial holes 28 which are arranged within the roll 6 and form gas jets through which gas may be supplied to the bore. The means for sup-

plying gas to the hollow shaft 16 comprises a short pipe 30 secured in one end of the shaft and projecting through a slot 32 formed in the corresponding side bar of the roll carrier. This pipe is connected by a union 34 with a supply pipe 36 which extends along the side of the roll carrier and is supported by a bearing 38 through which it slides freely during the oscillation of the leveling roll. The free end of the pipe 36 is connected by a flexible tube 40 with a gas supply pipe 42 which may be provided with a valve 44 for regulating the flow of gas to the gas jets within the leveling roll. The flexible connection between the pipe 36 and pipe 42 allows the roll carrier 8 to rise and fall and to tilt laterally without interfering with the supply of gas to the jets within the leveling roll.

The above construction provides a simple and efficient means for heating the leveling roll during the leveling operation without interfering with the movements of the roll requisite for properly leveling the sole, and without danger of soiling the sole engaging surface of the roll. It also enables the temperature to be readily regulated in accord-

ance with the character of the work being done and in such manner as to secure the best results.

Having explained the nature and object of the invention, and specifically described one form of mechanism in which it may be embodied, what is claimed is:—

A sole leveling machine comprising a roll carrier having a slotted side bar, a yoke slidingly supported in the carrier, means for vibrating the yoke within the carrier, a non-rotatable hollow shaft mounted in the yoke and having a series of fuel passages communicating with the central bore, a fuel pipe connected to the end of the shaft and passing through the slot in the side bar, and an open ended hollow leveling roll journaled upon the shaft and heated by jets of flame within the roll and issuing from the fuel passages in the shaft, the products of combustion passing out through the open end of the roll.

WILLIAM C. BAXTER.
